HOOK AND CLEAT COMBINATION

Serafin G. Lopez, New York, N.Y.

Application March 1, 1954, Serial No. 413,113

1 Claim. (Cl. 24—123)

The present invention relates generally to a hook and cleat combination for use in supporting scaffolds, boatswain's chair, pad eyes on ships, or the like and for snubbing the supporting rope or line of associating hoisting tackle. The invention is an improvement of my copending application Serial No. 313,925, filed October 9, 1952, now abandoned.

It is an object of the present invention to provide a fitting for connecting the boatswain's chair, scaffold, or pad eyes on ships, to supporting tackle or other supporting means, which fitting includes a hook having preferably an oval groove relatively wide in the center part of the hook and narrow in the extreme parts of the hook to adapt the hook for association with different sizes of eyes to be connected therewith.

It is a further object of the present invention to provide a hook per se having a substantially oval shaped groove wide in the center part of the hook and narrow at its ends for use in connection with different sizes of eyes to be connected thereto.

It is still another object of the present invention to provide a hook which may form a combination with a cleat or for use as an independent element, the hook having a groove wherein the center part of the groove is wide and the outer parts are narrow to accommodate different sizes of eyes and yet, be capable of substantially preventing rotation of the eye or swivelling thereof when in use, the eye being used as an instrumentality for supporting a boatswain's chair, scaffold, or other device.

It is yet another object of the present invention to provide standard hooks with the aforementioned grooves to enable holding of wood blocks and ropes of tackle in one position to facilitate manipulation by the operator.

Yet another object of the present invention is to provide in a hook a compound oval groove to prevent the hook and cleat combination from turning to the right or to the left and to maintain the device in proper position to enable the operator to fasten the rope.

It is still a further object of the present invention to so design the cleat portion of the combination to conform to the shape of the hoisting rope conventionally used on scaffolds, boatswains' chairs or the like.

In hoisting equipment, such as boatswains' chairs or scaffolds, the chair or scaffold is supported by tackle including a rope and block pulleys so that it may be conveniently raised or lowered. In such circumstances it is desirable to permit adjustment of the elevation of the chair or scaffold at the location of the chair or scaffold, and for this purpose the free end of the supporting rope is usually removably secured to a fitting attached to the boatswain's chair or scaffold so that the tackle may be adjusted or held in a fixed position. Since boatswains' chairs or scaffolds are usually employed for work at relatively high or great heights, for example, in painting or repairing the masts of ships or in painting buildings and bridge structures, it is important that the chair or scaffold be held against rotary oscillation. For this pur-

pose a fitting is provided, including a cleat having a portion for securing the free end of the tackle rope thereto for holding the rope and a hook portion to which the eye associated with the chair or scaffold is suspended, and it is this hook which is provided with a groove formed so as to prevent the chair or scaffold from rotary oscillation. This groove maintains the device in proper position to enable the operator to fasten the rope.

In accordance with a preferred embodiment of the present invention, the foregoing objects, and other objects, features and advantages appearing in the following detailed description, are achieved by providing a fitting for interposition between tackle and a boatswain's chair or scaffold and which includes an elongated member or shank having an eye at one end for attachment to the tackle and a snap-hook at the other end for supporting through an eye, the chair or scaffold. This snap hook has a specially constructed groove for the purposes hereinabove outlined. Intermediate the ends of the elongated member or shank lateral arms or members extend in opposite directions, to each of which arms at the end thereof there is provided a vertical stop member. The lateral cross-members or arms are provided with reduced rounded portions where they join the shank to conform to the shape of the hoisting rope conventionally used with boatswains' chairs and scaffolds. The vertical stop members prevent the rope from slipping off the fitting when the rope engages the cross-members or arms.

With respect to the transverse groove provided in the bight of the hook portion of the hook and cleat combination, this groove which is preferably formed in the general shape of an oval can be made wide in the center part of the hook and narrow in the outer parts of the hook, or the groove may be of uniform width from outer part to outer part including the center part of the hook and of uniform depth. As heretofore stated the transverse oval groove on the hook portion makes provision for the steel eyes of the standard scaffolds and the eyes of the boatswain's chair disclosed in my said copending application, in which latter case the chair eyes are supported, respectively, snugly in the transverse oval groove, preventing possible right and left relative movements of the chair and hook and cleat combination, and making it easy for the operator to fasten a rope to the cleat part and lowering of the chair or scaffold.

In order to facilitate understanding of the present invention, certain embodiments thereof are hereinafter described in detail and illustrated in the accompanying drawings forming a part hereof and wherein:

Fig. 1 is a perspective view of a fitting including a snap-hook and cleat combination constructed in accordance with the present invention;

Fig. 2 is a perspective view of the snap-hook portion also showing a fragment of the cleat portion of the device;

Fig. 3 is a front view of the snap-hook portion of the device, the latch being removed for clarity;

Fig. 4 is a front view of the lower portion of the snap-hook and cleat combination, showing a modified hook in engagement with an eye; and

Fig. 5 is a perspective view of the hook portion seen in Fig. 4.

Referring to the drawings in detail, and initially to Figs. 1 to 3 thereof, a fitting constructed in accordance with a preferred embodiment of the present invention is there illustrated and generally identified by the reference numeral 10. The fitting 10 includes an elongated member or shank 11 having suitable means at its upper end for attachment to the rope or a pulley-block of tackle provided for supporting the fitting, and which

in the illustrated construction consists of an eye or ring 12 having an opening 13 and which is integral with the shank 11. The shank 11, at its lower end, has depending from it an integral hook portion 11a, 11b and 11c, the latter indicating the bight of the hook. Intermediate the ends of the elongated or shank member 11, the lateral arms or cross-members 15 extend in opposite directions, to which of each arms at the end thereof there is provided a vertical stop member 14. The lateral cross-members or arms 15 are provided with reduced rounded portions where they join the shank 11 to accommodate the hoisting rope conventionally used with boatswains' chairs and scaffolds. These reduced rounded portions 31 may be clearly seen in Fig. 4. The vertical stop members 14 prevent the rope from slipping off the fitting when the rope engages the cross-members 15. A resilient or spring operated latch 17 is pivoted by means of a pin 18 to ears 16 projecting from the lower portion of shank 11 to form the movable part of the snap hook. A spring 19 encircles the pin 18 and has one end abutting against the latch 17 and its other end against the shank 11 between the ears 16. The upwardly extending end portion 21 of the hook portion of the fitting is provided with a substantially rectangular recess 20 which besides providing an accommodation for the tip of the latch 17 also provides shoulders 20a to protect the same from possible damage and to maintain the latch in proper position. The grooves 23, 24 are formed in the inner face 22 of the hook.

As clearly seen in Fig. 2, the portion 11a of the hook member is preferably bowed outwardly to provide the necessary space for the accommodation of the eye of the article to be supported, such as eye 28 of Fig. 4, and also to bring the hook portion 11b into substantial alignment with the shank 11 and spring operated or snap latch 17.

The drawings show the transverse groove in the bight 11c of the hook member as being substantially oval-shaped, with the center portion 23 wider than the remaining portions 24, to accommodate eyes (used to connect boatswains' chairs, scaffolds, etc., to the hook-cleat combination) of different diameters. An eye of one diameter may fit snugly in the center portion 23 of the groove, whereas an eye of smaller diameter may fit snugly in the narrower groove portions 24, the purpose being to so snugly fit the eye in the groove so as to prevent relative right or left turning or sidewise swinging between the hook-cleat combination and the eye and/or article to which the eye is connected.

Figs. 4 and 5 show the hook members 25, 26, with the spring-operated or snap-latch eliminated. In this embodiment it is preferable to provide an inwardly directed bend 27 at the free end of the hook to bring portion 26 into the juncture of shank 11 and the hook,

providing almost a closed hook. In this embodiment the eye 28 comprising the almost annular upper portion 29 and outward extending arms 30 will have to be threaded through the loop of the hook from its open end.

The eye 28 may form part of a boatswain's chair assembly as disclosed in my copending application Serial No. 174,402, filed July 18, 1950 now abandoned, or it may form part (either in its identical form or in any other form or variation) of any article or device to connect the latter to the hook-cleat combination.

Furthermore, the hook device herein described may be employed separately from or as an independent unit for its intended purpose.

Although the present invention has been described in some detail by way of illustration and example for purposes of clarity of understanding, it is understood that certain changes and modifications may be made within the spirit of the invention and the scope of the appended claim.

I claim:

Hook and cleat combination for use with rope and tackle comprising an elongated shank member having means at one end for connection to the tackle and means at the other end for connection to an eye member, arms extending laterally from said elongated shank in opposite directions and intermediate the ends of said shank, elongated end members at the end of said arms extending substantially parallel to said shank, and a hook member extending from the lower end of said shank, said hook member having a transverse groove in the bight thereof for receiving said eye member, each of said arms having its portion adjacent said shank of reduced cross-section for receiving a turn of said rope and holding said turn adjacent to said shank.
